CLAIM

The ornamental design for a biodegradable surgical staple, as shown and described.

DESCRIPTION

FIG. 1 is a side elevational view of a biodegradable surgical staple showing my new design, with the opposite side being a mirror image;

FIG. 2 is a front elevational view thereof, with the rear being a mirror image;

FIG. 3 is a top plan view thereof;

FIG. 4 is a bottom plan view thereof;

FIG. 5 is a bottom perspective view thereof.

Fig. 1.Fig. 3.Fig. 2.Fig. 5.Fig. 4.
